EXCAVATING APPARATUS

Raymond S. Weimer, Morris, Ill.

Application February 16, 1938, Serial No. 190,729

6 Claims. (Cl. 37—135)

This invention relates to improvements to excavating apparatus.

In excavating apparatus of the drag line type, the buckets employed are attached to haul lines operated from a source of power for hauling the buckets to fill the same and are attached also to boom carried hoist lines by means of which the loaded bucket may be elevated and transported to discharging position. Since the haul line does not provide rigid means by which the excavating or digging angle of the bucket can be controlled during the digging or filling operation, the point of attachment of the haul line, or its branches, have been so located as to avoid the forward upsetting or overturning of the bucket as it encounters resistance during the loading or digging operation. Thus it has been common practice to attach the haul line to a bucket at opposite points above the cutting edge or points of the teeth and forwardly of the latter whereby when tension is applied to the haul line the cutting edge or teeth will be forced into the earth, thus tilting the rear end of the bucket upwardly. This tilting action is limited to that angle wherein the points of attachment of the haul line, and the teeth or cutting edge of the bucket are alined with the source of the power or tension exerted on the haul line. In order to provide points of attachment for the haul line which are located forwardly of the cutting edge, it has been common practice to extend the side walls of the bucket forwardly and attach the haul line branches thereof to those projecting ends at elevations which will determine the maximum digging or cutting angle of the bucket. In some instances such projecting ends have been pivoted to form closure members or gates which have been designed to close partially upon the forward portion of the load to prevent loss thereof during elevation and transportation to the place of deposit.

Such forwardly projecting portions of the side walls of the bucket, whether integral with the walls or hinged thereto, add considerable weight to the bucket which lessens its pay-load carrying capacity. Since such over-hanging or projecting side walls are of cantilever form their use has necessitated the substantial addition to the structural weight of the bucket in so constructing the end portions so as to withstand the stresses and impacts normally encountered in drag line operation.

One object of the invention is to provide a bucket provided with articulately attached stabilizing members arranged to cooperate with the

haul and hoist lines of the bucket for stabilizing the bucket at predetermined working angles.

Another object of the present invention is to provide a bucket adapted for use with drag-line equipment having a pair of connected articulate stabilizing members extending from the side walls forwardly of the cutting edge in lieu of the integral or hinged side wall sections above mentioned and attached to haul line branches

10 at points forwardly of the bucket and so cooperating with said branches as to predetermine the excavating angle of the bucket. This pair of members can be made lighter in weight than the overhanging side walls of the prior art where-
15 by a sturdier bucket construction can be employed of the same load-carrying capacity without increasing the total load on the hoisting equipment or a larger capacity bucket may be employed with like results.

20 Another object of the invention is to provide a bucket having relatively articulate forwardly projecting compression members which do not interfere with the free ingress of material into the bucket during loading and which may be so
25 attached to the hoist line branches or attaching means that during elevation of the loaded bucket said members can be swung rearwardly against the forward portions of the load to reduce spillage of the load material. Such articulately
30 connected members being non-rigid with respect to the side walls of the bucket do not transfer to the bucket proper the full force of impacts im-
35 parted thereto in use and hence the improved bucket is more durable in use.

35 An additional object of the invention is to provide articulate stabilizing members extending generally forwardly of the bucket which cooperate with the haul and hoist line attaching means in retaining the bucket in load-carrying position
40 during elevation and transportation of the load to the place of deposit.

45 Other objects and advantages of the present improvements will be apparent from a consideration of the following specification and accompanying drawings wherein,

Figure 1 is a side elevation of an improved bucket embodying the present invention.

Figure 2 is a top plan view thereof.

50 Figure 3 is a side view of a bucket shown in a predetermined excavating or digging position.

Figure 4 is a side elevation of a loaded bucket in elevated position;

55 Figure 5 is a front elevation of a loaded elevated bucket;

Figures 6 and 7 are modifications of the invention shown in the preceding figures; and

Figure 8 illustrates a further modification.

In the embodiments of the invention illustrated, the bucket 10 is of the flaring wall, rearwardly dumping type shown in my U. S. Patent No. 2,096,773, granted October 26, 1937, although the present invention may be utilized in conjunction with a conventional vertical walled bucket. As shown in the drawings, the bucket 10 is provided with side walls 11, a rear wall 12 and a bottom wall 13, the forward edges 14 of which constitutes a cutting edge or lip and may be provided with teeth 15 of appropriate form. It will be observed that the side walls 11 do not extend beyond the cutting edge, in fact, in the particular form of bucket illustrated, the walls terminate at their forward ends at the rear of the points of the teeth which constitute the fulcrum of the bucket as the teeth meet resistance in digging whereby the bucket tilts more or less forwardly as indicated in Fig. 3. Insofar as the stabilization of the bucket is concerned, it is not particularly pertinent whether the forward ends of the side walls terminate at, forward of, or to the rear of a vertical plane through the teeth points.

A flexible haul or drag line or cable 16 is provided with attaching means such as the chain branches 17 which are attached to the side walls 11 by eyes or other suitable means. Since the effective point of attachment of the haul line to the bucket is on a horizontal axis at the rear of the cutting edge or teeth points, it is obvious that should the teeth meet sufficient resistance in digging, the tension of the drag line could tilt the bucket forwardly sufficiently to overturn it. For the purpose of preventing such excessive forward tilting beyond a predetermined excavating angle illustrated in Fig. 3, compression 40 stabilizing members 19, which may be flanged bars or other elements of adequate stiffness, are articulately attached to the side walls and to the corresponding branches 17. The means for attaching the compression or strut members 19 to the bucket side walls are shown as comprising connected eye members 20 and 21, while other suitable members or eyes 22 and 23 may be employed to connect the lower ends of the compression members 19 articulately to the branches 17.

With the arrangement described it will be observed that as the teeth 15 enter the earth as the bucket is drawn forwardly by the haul line 16, the teeth constitute an axis or fulcrum around which the bucket tends to tilt forwardly. With the branches 17 connected to the side walls on an axis above and to the rear of the teeth points, such tilting movement might continue, under conditions affording sufficient digging resistance, until the bucket reached the position in which the pivotal axis represented by the eyes 18 were in a straight line connecting the teeth points and the source of power exerted on the haul line, in which position the bucket would be substantially inverted. With the strut or compression members 19 as shown, however, such tilting movement of the bucket beyond a predetermined excavating angle, as shown in Fig. 3, cannot occur. As illustrated in said figure, the members 19 resist tilting movement beyond the angle shown due to the connection of the same to the upper portions of the respective side walls 11 and the corresponding branches 17 which are taut during the filling or loading operation.

It will be obvious that the weight of the mem-

bers 19 is much less than the weight of the portions of the side walls of prior buckets which have necessarily been extended forwardly adequately to afford means for attaching the branches of the haul line on an axis sufficiently in advance of the teeth to limit forward tilting of the bucket beyond a predetermined digging angle. With the present bucket the saving in weight over prior buckets can be utilized in added pay-load carrying capacity or in strengthening the bucket to render it more durable.

During elevation, the bucket illustrated when normally loaded tends to tilt rearwardly to load-discharging position, the bucket tilting about the axis defined by pivotal connections 25, 25 by means of which the branches 26, 26 of the hoist line are attached to the bucket. The pivotal connections 25, 25 may be coating ears, as shown, whereby the bucket can tilt freely to load-discharging position when tension on the haul line 16 is released since such pivotal axis of the bucket is preferably located forwardly of and below the center of gravity of a normal load indicated at C. G. in Fig. 4.

When tension is applied to hoist line 28 to elevate the bucket, flexible members 27, which are attached to the hoist line branches 26 at 27^a are made taut, that is, they are drawn from the slack condition shown in Fig. 3 to the tensioned condition shown in Fig. 4. Such action of the members 27 draws the forward ends of the members 19 rearwardly and inwardly against a forward portion of the load and reduces the loss thereof from the forward end of the bucket during elevation and transportation to the place of deposit. The sections of the branches 17 between the connections 18 and 23 (indicated at 17^a) will likewise be drawn over a face of the load projecting beyond the end walls and reduce loss also as illustrated in Figs. 4 and 5.

In Figs. 6 and 7 additional flexible members 29 and 30 respectively are shown which cooperate with the members 19 and 17^a in preventing load losses, members 29 extending between the forward edges of the side walls and the corresponding members 19 while the members 30 extend between members 19 and the corresponding haul line branch sections 17^a. These members, that is 17^a, 19 and 29 or 30 form a net-like formation which reduces losses from forward portions of the loads, as will be seen.

Should the bucket be so loaded that the center of gravity is located forwardly and above the pivotal axis (25-25) the bucket will tend to tilt forwardly but such action will be restrained by the parts and arrangement thereof disclosed. When tension is applied to the hoist line 28 and the branches 26 thereof to elevate the load, tension is also applied to the haul line 16 to restrain a normal load from tilting the bucket rearwardly to discharging position. During such elevation the haul line is, of course, paid out as the hoist line is taken in by the power means not shown herein but illustrated in my above mentioned patent. When the haul line branches are taut, as mentioned, the members 19 are held rigid due to the connections of the same at the upper ends to the side walls of the bucket and at their lower ends to the branches 17. The bucket thus cannot tilt forwardly about the axis 25-25 under these conditions but must tilt, if at all, about the points 22-22. The axis determined by the points 22-22 is sufficiently spaced from 75 the forward end of the bucket as to preclude

the forward tilting to load-discharging position by any load which the bucket is designed to carry.

While a loaded bucket is being elevated, the hoist line carried by the boom (not shown) is taken in by well known mechanism and the haul line paid out until the bucket has been moved upwardly and outwardly as desired and swung to the position of discharge. Tension on the haul line is then released and if the load is normal, the bucket will tilt rearwardly to the dotted line position of Fig. 4 to discharge the load. Should the load be carried substantially forwardly of the bucket, it may tilt forwardly to discharge the load as the tension on the haul line is released or a forward portion of the load may be discharged from the front of the bucket whereupon the center of gravity of the loaded bucket, having shifted to the left of the vertical plane through the pivotal axis 25-25 of the bucket, the bucket will tilt rearwardly to discharge the remaining portion of the load.

It will be observed that the members 19 thus perform desirable functions in the operation of the drag line equipment, that is, by their length and the points of connection of the same to the bucket side walls and to the haul line branches they predetermine the maximum excavating or digging angle of the bucket during loading operations; they cooperate with other portions of the apparatus in restraining both forward and rearward tilting to a load-discharging position during elevation and transportation of the load and they also cooperate with haul line branch sections 17a or in the modifications shown in Figs. 6 and 7 with members 29 and 30, respectively, in reducing load losses during elevation and transportation to the place of deposit. It will be observed also that as a loaded bucket is elevated above the loading position, the force exerted by the haul line will be applied through the members 19 to the upper portion of the bucket at points substantially above the pivotal axis 25-25. Hence, less tension on the haul line will be required in restraining the tendency of the bucket to tilt rearwardly when carrying a normal load. The less the tension on the haul line, the more nearly under the boom point the load can be elevated and hence such arrangement increases the effective length of the boom and the excavating range of the apparatus. Since the tension applied to the members 27 during elevation tends to swing the forward ends of the stabilizing members inwardly and rearwardly, the advantage in resisting rearward tilting afforded by the members 19 is somewhat reduced as will be seen. If desired, flexible members 31 may be attached to the ears 28 and to the branches 17 at points more remote from the bucket, as shown in Fig. 8, whereby tension from the haul line will be applied more nearly in a straight line to the upper portions of the bucket as it is elevated whereby less tension will be required to resist tilting and the advantage above mentioned more fully attained.

Where a bucket having flaring side and rear walls is employed, the hoist line branches preferably are attached to the inner portions of the bucket as shown in the drawings, no spreader bars for such lines being necessary. Where a bucket having vertical side walls is employed, the hoist branch lines may be attached exteriorly of the side walls, if desired, in which case a conventional spreader bar should be used. In the arrangement illustrated, however, when the

bucket tilts rearwardly to the load discharging position, none of the rigging, that is, the branch hoist lines 26, members 27 or members 19 obstruct the free pivotal movement of the bucket 5 when tension on the haul line is released at dumping position. The load is thus quickly and completely discharged from the bucket and away from the apparatus.

Since the weight of the members 19 is considerably less than the forwardly extending ends of the side walls of the bucket of the prior art, such saving in weight can be taken advantage of in constructing an improved bucket having greater pay-load carrying capacity without imposing additional load on the power operating mechanism. The members 19 being articulately connected to the side walls do not impart thereto all the stresses and impacts received during normal use as is the case with integral projections of the side walls. For example, when a forwardly projecting side wall of a conventional bucket strikes a large rock, the teeth of the bucket may be forced from the earth or nearly so. Where a flexible member, such as 17a strikes a rock, it may be deflected to one side without materially interrupting the loading operation.

While certain embodiments of the invention have been illustrated and described for the purpose of illustration, it will be apparent that various changes may be made therein without departing from the spirit of the invention.

I claim:

1. A drag bucket structure comprising a pair of flexible haul line attaching members attached to the bucket side walls, a pair of cooperating stabilizing compression members each articulately attached to a side wall of the bucket at a point above the point of attachment of the corresponding flexible member for limiting at a predetermined angle the forward tilting of the bucket about the cutting edge by tension exerted on said haul line attaching members during loading operations, a pair of hoist line attaching members pivotally attached at opposite points to said side walls, and members extending from said hoist line attaching means forwardly and downwardly and connected at the forward ends thereof to said compression members for swinging the forward ends of the latter inwardly and rearwardly into confining contact with a forward portion of a load as tension is applied to said hoist line attaching members in elevating the bucket.

2. The combination with an excavating bucket, of a pair of flexible drag line attaching members attached to the side walls of the bucket, a pair of hoist line attaching members pivotally attached to the bucket for enabling the latter to tilt on a horizontal axis to dumping position, a pair of stabilizing compression members each articulately connected adjacent the forward end 60 thereof to one of said haul line attaching members and extending upwardly and rearwardly into articulate connection with an upper forward portion of the corresponding side wall of the bucket and cooperating during loading operations 65 with said haul line attaching members for restraining forward tilting of the bucket beyond a predetermined excavating angle and means operable by said hoist line attaching members for swinging said compression members into confining contact with the forward portion of a load upon the application of tension to said hoist line.

3. An excavating bucket comprising haul and hoist line attaching members, stabilizing mem-

bers movably attached at the forward ends to said attaching members and attached at the rear ends to the forward end of said bucket for limiting tilting action of the bucket during loading and whereby upon elevation of the bucket said stabilizing members are swung rearwardly by said hoist line attaching members into confining contact with a forward portion of the load of the bucket and transmit to the upper forward end of the bucket the force exerted by said haul line attaching members to resist rearward tilting of the bucket, and additional load confining members attached to said stabilizing members and movable therewith into contact with the load.

4. An excavating bucket comprising a bottom, rear and side walls provided with hoist line attaching means pivotally attached thereto at opposite points defining the pivotal axis of the bucket, said axis being located forwardly of the center of gravity of the bucket and also forwardly of the center of the normal load space so as to tend to cause the bucket to tilt rearwardly for discharging the load over said rear wall, haul line attaching members secured to forward lower portions of the bucket, and members attached to said haul line attaching members at points forwardly of the bucket and extending rearwardly and upwardly into engagement with upper forward portions of the bucket for resisting rearward tilting of the bucket by tension applied to the same by the haul line attaching members during elevation of the bucket.

5. Excavating apparatus comprising a drag bucket, haul line rigging comprising a pair of

5 haul line attaching members secured to the forward end of the bucket and a pair of stabilizing compression members each articulately secured to a side wall of the bucket and extending forwardly and angularly with respect to the haul line attaching members into engagement with the latter at points forwardly of the bucket for limiting forward tilting of the bucket during loading operations, haul line members secured to the bucket, and members attached to and extending forwardly from the haul line members into engagement with said haul line rigging for drawing the forward ends of said stabilizing members inwardly and rearwardly into confining contact with the forward portion of a load as tension is applied to said haul line members in elevating the loaded bucket.

6. Excavating apparatus comprising a drag bucket, haul line rigging secured thereto and comprising haul line attaching members and swingable load confining members each connected to forward portions of the bucket, haul line members, and additional lines having the rear ends thereof connected to said haul line members and the forward ends connected to said haul line rigging at points adjacent the forward ends of said load confining members and being of such length as to cause the forward ends of said load confining members to be swung rearwardly and inwardly into contact with forward portions of a load in the bucket upon application of tension to said haul line members in elevating the loaded bucket.

RAYMOND S. WEIMER.
